UNITED STATES PATENT OFFICE.

JAMES McNAMARA, OF PORTLAND, AND ALBERT McNAMARA, OF OSWEGO, OREGON.

DEVICE FOR MOLDING AND LAUNCHING VESSELS WHICH ARE CONSTRUCTED OF CONCRETE, &c.

1,278,963.

Specification of Letters Patent. Patented Sept. 17, 1918.

Application filed February 26, 1918. Serial No. 219,196.

To all whom it may concern:

Be it known that we, JAMES McNAMARA, a subject of the King of England, residing in the United States, who has declared his intention of becoming an American citizen, of the city of Portland, county of Multnomah, State of Oregon, and ALBERT McNAMARA, a subject of the King of England, residing in the United States, who has declared his intention of becoming an American citizen, of the city of Oswego, county of Clackamas, and State of Oregon, have invented certain new and useful improvements in devices for molding and launching vessels which are constructed of concrete or any substance of a similar nature which requires a form for construction; and we do hereby declare that the following is a full, clear, and exact description of same, reference being had to the accompanying drawings, forming part of the specification, and to the letters and figures of reference marked thereon.

This invention relates more particularly to a device for molding and launching concrete vessels.

The object of this invention is to form a mold which can be used repeatedly without dismantling same, and when vessel is completed to furnish a rapid, easy and safe means for launching the vessel.

Referring to the accompanying drawings, Figure 1 is a plan of assembled mold. Fig. 2 is an elevation along parting line of mold. Fig. 3 is enlarged transverse section through center of mold. Fig. 4 is enlarged detail of clamping and alining device. Fig. 5 is diagram showing method of operating clamping screw simultaneously. Fig. 6 is a sectional elevation through engine room, showing my method of submerging and emerging pontoons.

Like letters and figures of reference in the several figures indicate the same or similar parts.

A¹ being a submersible pontoon of concrete, wood or metal, the interior of which, A², forms a mold for the exterior of the vessel. A³ indicates the recess in the mold for the vessel's stern keel. Pontoon A¹ is split along line A⁴ which parting line extends from the stem to the stern of the vessel and directly along its center line. The pontoon having been cut in halves by the parting line A⁴ is subdivided by the partitions A⁵, which

act as braces and bulkheads. A deck, A⁶, is formed above the bulkheads for storerooms and workshops. A⁷ are water tight compartments. A⁸ indicate the walls of the vessel under construction, showing the inside boxing removed.

In the face of the pontoon which is separated from the other half, that is along the line A⁴, is a channel or groove, B¹, extending the full length of the vessel, along its keel and then vertically along the bow and stern post portions of the molded vessel. B¹ is used to receive a similar shape of rib, B², which is mounted on the opposite pontoon, and also extends the full length of the vessel, that is from point B³ to B⁴, which are the terminals of the alining channels, B¹ and the rib B². The alining of the pontoon halves being determined, the securing of the parts in their relative positions is accomplished by screws B⁵, which clamp the rib portion, B², into the channel B¹. B⁶, which is a tapped plate, serves as a nut for B⁵, while B⁷ is a shoulder collar on B⁵ to hold same in place. B⁸ is a sprocket wheel for operating the screw B⁵ and is driven in common with similar screws, B⁹, by chain B¹⁰, which is supported on its idle portions by idler sprockets, B¹¹. Hand wheels, B¹², are used to impart the required motion to the clamping screws. A deck, B¹³, is placed over workshop and engine room space; B¹⁴. Shoulder B⁷ and sprocket B⁸ ride against the plate B¹⁴, which carries B⁵, and B¹⁵ are holes for B⁵.

C¹ is a motor for operating emerging pump C² through belt C³. Water is pumped from the bulkheads through pipe C⁴, and expelled by pump through pipe C⁵. The pump action exerted on the water in the individual bulkheads may be controlled by valves C⁶; C⁷ and C⁸ being check valves on pump C⁵.

Submerging of pontoons is accomplished by C⁹, which is a seacock for admitting water to the various bulkheads. The water emerging from mouth C¹⁰ and the inlet, being controlled by valve C¹¹, which is operated by rod C¹² and wheels C¹³, placed for convenience above deck A⁶. D¹ is an air passage, the purpose of which is to overcome the effect of changing the amount of water in each bulkhead.

The operation of our device is as follows: The two sections of the pontoon are brought

- together so rib B² will enter channel B¹ and permit operation of clamping device. If needed the parting line is calked and water let into bulkheads. The inner part of the 5 mold can be formed as is now customary with built up walls, and the process of putting in concrete can be started. As the work progresses and weight is added to the pontoons, water is taken from the bulkheads.
- 10 The outside of the mold at the upper edge can be made to conform with the shape of the gunwale of the completed vessel, or it can be made straight as indicated, so they will furnish walls for shop and engine decks.
- 15 When vessel is completed the pontoons are separated by unscrewing clamps so screws are entirely withdrawn from tapped plates and pontoons are gradually withdrawn, leaving new hull launched.
- 20 It must be apparent that our system will greatly reduce the cost of construction of molds, as they can be used repeatedly, while with the present system the entire superstructure and molds must be removed and 25 much of the lumber wasted. The second and even greater advantage is that of launching, which is automatic. The third advantage is transportation of supplies, which can be taken aboard the pontoons 30 from nearby vessels.

While we have thus described and illustrated our invention, it is not our intention that it shall be limited to this particular

form or shape, but that it shall cover all modifications of same that fall fairly within 35 the appended claims.

Having thus described our invention, what we claim as new and desire to secure by Letters Patent of the United States, is:

1. A form for concrete hulls, consisting 40 of a mold means constituting a pontoon structure, and means for submerging pontoon structure.
2. The combined forming and launching device for concrete ships, consisting of a 45 divided hull forming means, constituting a sectional pontoon means, section alining means, a section clamping and releasing means and pontoon submerging means.
3. In a launching form for concrete float- 50 ing bodies, consisting of a floating, molding form means, which is divided into sections for the purpose of freeing the product and each of the sections floating independently and capable of being reunited to receive the 55 next materials to be molded.
4. In a device for molding and launching concrete ships, consisting of a submersible split mold means having a means for automatically alining mold, while being united 60 and a clamping and releasing means for holding and releasing sections of mold means.

JAMES McNAMARA.
ALBERT McNAMARA.
